UNITED STATES PATENT OFFICE.

EMLEN G. PENROSE, HARVEY S. NUTTING, AND WILLIAM H. SMITH, OF
TAMA CITY, IOWA.

COMPOUND FOR EXTINGUISHING FIRES.

SPECIFICATION forming part of Letters Patent No. 366,126, dated July 5, 1887.

Application filed June 8, 1886. Serial No. 204,529. (Specimens.)

To all whom it may concern:

Be it known that we, EMLEN G. PENROSE, HARVEY S. NUTTING, and WILLIAM H. SMITH, citizens of the United States of America, residing at Tama City, in the county of Tama and State of Iowa, have invented certain new and useful Improvements in Hand Fire-Extinguishers, of which the following is a specification.

10 This invention pertains to certain new and useful improvements in fire-extinguishing compounds; and it consists in the combination of ingredients, substantially as herein-after fully set forth and claimed.

15 In the preparation of our fire-extinguishing compound we take carbonate of potash, two parts; carbonate of magnesia, one part; saltpeter, two parts; saleratus, two parts, and sulphate of iron, two parts. These ingredients we dissolve in water into a liquid, which we place in glass bottles, preferably of globe shape. By throwing a bottle containing this compound into a fire the bottle will immediately or eventually break, by reason of

the heat of the fire, causing the compound to 25 spread itself, and the vapors arising therefrom will quench or entirely extinguish the fire.

We are aware that each of the ingredients of our compound is old for the purpose; but 30 when combined as herein specified a new and better compound is obtained.

Having thus fully described our invention, what we claim, and desire to secure by Letters Patent, is—

35 A fire-extinguishing compound composed of carbonate of potash, two parts; carbonate of magnesia, one part; saltpeter, two parts; saleratus, two parts, and sulphate of iron, two parts, as specified.

In testimony whereof we affix our signatures in presence of two witnesses.

EMLEN G. PENROSE.
HARVEY S. NUTTING.
WILLIAM H. SMITH.

Witnesses:

FRANK ESTERLY,
STEPHEN SMITH.
